UNITED STATES PATENT OFFICE.

KATHERINE B. FULD, OF BALTIMORE, MARYLAND, ASSIGNOR TO WILLIAM FULD, OF BALTIMORE, MARYLAND.

FIGURE WHEELED TOY.

1,398,426.

Specification of Letters Patent. Patented Nov. 29, 1921.

Application filed January 11, 1921. Serial No. 436,419.

To all whom it may concern:

Be it known that I, KATHERINE B. FULD, a citizen of the United States, residing at Baltimore, in the county of Baltimore and 5 State of Maryland, have invented certain new and useful Improvements in Figure Wheeled Toys, of which the following is a specification.

This invention relates to toys and has for 10 an object the provision of a wheeled toy of simple construction which shall have an amusing movement.

A further object of the invention is the provision of a toy which with a very simple 15 operating mechanism may provide movement of a plurality of figures.

A further object is the provision of a toy which is cheap to manufacture and is not likely to get out of order.

20 An illustrative embodiment of the invention is shown in the accompanying drawing wherein like reference characters refer to like parts, and wherein:

Figure 1 is a side elevation with parts 25 broken away and in section to more clearly show the mechanism and with a different position of the parts shown in dotted lines.

Fig. 2 is a plan view with a portion of each of two elements broken away to more 30 clearly show the construction of parts.

Fig. 3 is a detail section on line 3—3 of Fig. 2 showing the structure of front axle mounting.

The base 5 of the toy is mounted on the 35 front wheels 6 and the rear wheels 7. For attachment of the wheels to the base, blocks 8 for the front wheels and blocks 9 for the rear wheels are secured to the base 5 as by glue or nails. The rear wheels 7 may be 40 pivotally secured to the blocks 9 by driving a nail or a screw through a hole in the center of each wheel into the adjacent block.

The front wheels 6 are mounted on the ends of the axle 10 in such a manner that 45 the axle will be caused to revolve with the wheels. This may be accomplished by squaring the axle or by a tight fit or in any other well known manner. For convenient assembly of the axle with the wheels 50 already secured thereto the blocks 8 may be formed with a slot as 11, Fig. 3, and the axle may be retained therein by driving a nail 12 into the end of the block intersecting the slot 11 below the axle.

55 To drive the moving parts of the toy a

crank 13 is formed in the central portion of the axle and a connecting rod 14 is connected thereto.

The main figure, in the form chosen for purposes of illustration made to represent a 60 goat, is rigidly secured to the base 5 as by nails 15 and has the head 16 pivotally mounted on the body 17. To this end a slot 18 is produced in the proper location on the body 17 and the neck 19 has a reduced 65 portion 20 adapted to enter the slot after which a pin 21 is passed through the body and reduced portion of the neck. The head is thus oscillatably mounted upon the body. To cause movements of oscillation of the 70 head the connecting rod 14 may be connected to the nose 22 as by means of a staple or screw eye 23.

A second figure 24, being shown in the 75 form of a monkey for purposes of illustration, is oscillatably mounted on the back of the first figure 17 as by being slotted at 25 to provide two projecting portions 26 one of which may pass on each side of the body 17, and which are then pivotally secured 80 thereto as by a pin 27 passed through the overlapping parts.

To cause motion of the figure 24 without any added driving mechanism connected to the wheels of the toy, a portion of the moving portion of the first or main figure is utilized as a cam. In the form shown the horn 28 is so formed that the figure 24 rests on the rounded cam surface of the horn by gravity, the nose 29 of the figure 24 being 90 allowed to contact with the horn.

The fore legs 30 of the figure 24 may be positioned to contact the back of the figure 17 at the lowest point of oscillation of the parts, and when so formed gives an added 95 security against breakage of the portion 28 bearing the cam surface, in the event, for instance, of a child sitting on the figure 24. An attachment for a cord by which to draw the toy may be provided, a hole 31 being 100 shown for the purpose.

When the toy is drawn the crank 13 will cause an oscillation of the head 16 giving an appearance of a nodding motion which motion will be transmitted to the figure 24. 105

Minor changes may be made in the physical embodiment of the invention without departing from its spirit.

I claim:

1. A toy comprising, in combination, a 110

wheel-equipped platform, a figure having a body portion, an oscillating member pivotally connected to said body portion and having a cam surface thereon, means connecting the wheel members and said oscillating member to actuate the latter in the movement of the former, and a second figure pivoted to the body portion of said first figure and having its free forward end resting on the cam surface of said oscillating member to be rocked by the movements thereof.

2. A toy comprising, in combination, a base, an axle mounted on said base having a

crank formed thereon, wheels rigidly mounted on said axle, a figure having a body rigidly secured upon said base, a head having a neck portion oscillatably mounted on said body, a connecting rod connecting said head and axle for oscillation of the head, a cam surface carried by said head, a secondary figure oscillatably mounted on said body and resting on said cam surface whereby oscillation of the head will cause like movement of the secondary figure.

In testimony whereof I affix my signature. 25
KATHERINE B. FULD.
